HOOKER ELECTROCHEMICAL COMPANY, OF NEW YORK, N. Y., A CORPORATION OF
NEW YORK.

ELECTROLYTIC CELL.

1,306,237.

Specification of Letters Patent. Patented June 10, 1919.

Application filed July 24, 1917. Serial No. 182,504.

To all whom it may concern:

Be it known that I, CLINTON PAUL TOWNSEND, a citizen of the United States, residing at Washington, in the District of Columbia, have invented certain new and useful Improvements in Electrolytic Cells, of which the following is a specification.

This invention relates to electrolytic cells for producing chlorin or other gaseous products, a primary object of the invention being to provide in conjunction with electrolytic cells producing chlorin or other gases, means for avoiding the diluting effect upon such gases of atmospheric air entering the cell through fissures or leaks in the cell structure, or with the inflowing electrolyte, or otherwise. The invention comprises also the method whereby this result is attained. The invention will be described as applied to a cell of the diaphragm type producing chlorin and caustic soda by the electrolytic decomposition of brine, but as will herein-after appear the invention is not restricted to cells of this particular type.

It is desirable from an operating standpoint to maintain in chlorin-producing cells a gas-pressure which does not exceed atmospheric pressure, and which is preferably slightly below atmospheric, since under these conditions no escape of chlorin can occur into the atmosphere through such minute fissures as are liable to exist in the structure, for example in the cell-body or cover, around the anode leads, etc. This is usually accomplished by withdrawing the chlorin under slight suction produced by a fan or equivalent means, and presents the disadvantage (for certain purposes for which a highly concentrated gas is desired) that the chlorin is diluted to whatever extent air may enter the cell from without.

The purpose of this invention is to secure the operating advantage due to maintaining atmospheric or lower pressures within the cell while at the same time removing a substantial proportion of the evolved chlorin or other gas, or even substantially all thereof, under a pressure which may slightly or considerably exceed that of the atmosphere. This is accomplished in a representative embodiment of the invention by providing a plurality of gas outlets from the anode compartment

of the cell, one outlet permitting the maintenance through a fan connection or otherwise of pressures not exceeding atmospheric pressures above the brine level in the cell; and another outlet or outlets serving for the simultaneous escape of chlorin under a definite positive pressure. This positive pressure may of course be exceedingly slight, but should be sufficient to cause a definite flow of the gas into the gas distributing or collecting system. Or if desired, the positive pressure may attain considerable magnitudes, as explained below.

The accompanying drawing, in which the figure is a transverse vertical section of an electrolytic cell of the vertical-diaphragm type, illustrates one mode of carrying the invention into effect. In said drawing, 1 represents the concrete base of the cell, and 2 one of the end walls thereof, the cell-body being of elongated U-form with vertical end-members. 3, 3 represents side plates which may be of Portland cement or cement mixtures, or of any appropriate insulating or insulated material, these side plates extending between the upper portions of the end-members 2. 4 is the cell cover. The sides of the cell are closed by sheet-metal flanged cathode compartments 5, provided with the usual outlets for caustic solution and hydrogen, and which may be secured in place in any desired way, for example by means of wedges or cams 6 passing through slots in the horizontal angle-bars 7, and engaging the flanges 8 of the cathode compartments. 9 represents the perforated steel plate cathodes and 10 the diaphragms, usually of asbestos paper. 11 are the graphite anodes and 12 the anode leads, also of graphite, the latter illustrated as projecting upwardly through the cell-cover 4. 13 indicates the anode electrolyte (anolyte) consisting in this case of a strong sodium chlorid solution. Any appropriate means may be used for maintaining and regulating the brine level, as for example an overflow 14; or any appropriate level-controlling device may be used in those cases where no overflow is desired. 15 represents a gas outlet leading from the upper portion or gas-space of the anode compartment. It is at this point that sufficient suction is applied (for example by means of

a suction fan indicated at 15') to maintain a very slight sub-atmospheric pressure within the cell.

As a typical means for withdrawing chlorin gas under positive pressure even while maintaining a sub-atmospheric pressure within the gas-space of the cell, I have illustrated longitudinal collecting channels 16 formed within or extending along the lower edges of the side plates 3, and communicating with gas conduits 17 extending upwardly through these side plates. These conduits (or the gas system connected therewith) are provided with appropriate pressure controlling devices, typified by the cocks 18. Inasmuch as the lower edges of the collecting channels 16 are below the normal liquid level in the anode compartment (indicated at 19) it will be obvious that the chlorin may be drawn from the conduits 17 under any pressure up to that represented by the hydrostatic head of liquid above the depending walls of these channels. As stated above, a very small positive pressure will suffice to secure the desired advantage of freedom from dilution by infiltration of atmospheric air; but it will be understood that the gas may if desired be collected under very considerable pressures by correspondingly increasing the hydrostatic head of liquid in the anode compartment.

The term "positive pressure" is used herein to include any degree of pressure

which will suffice under operating conditions to prevent dilution of chlorin by the infiltration of atmospheric air. 35

I claim:—

1. In combination with an electrolytic cell having a gas-space, means for maintaining atmospheric or lower pressures within said gas-space, and means for collecting the evolved gas before it reaches said gas-space. 40

2. In combination with an electrolytic cell for producing chlorin, means for maintaining atmospheric or lower pressures within the gas-space of the cell, and means disposed below the surface of the electrolyte for collecting the evolved chlorin before it reaches said gas-space. 45

3. In the electrolytic production of chlorin, the step which consists in simultaneously withdrawing the evolved chlorin at a plurality of points and at differing pressures. 50

4. In the electrolytic production of chlorin, the steps which consist in withdrawing a portion at least of the evolved gas under positive pressure, while maintaining within the gas-space of the cell a pressure not exceeding atmospheric. 55

5. In the electrolytic production of chlorin, the steps which consist in withdrawing a portion at least of the evolved chlorin under positive pressure while maintaining a sub-atmospheric pressure within the cell. 60

In testimony whereof, I affix my signature. 65
CLINTON PAUL TOWNSEND.
